UNITED STATES PATENT OFFICE.

HARRY M. SNOW, OF KALAMAZOO, MICHIGAN, AND NATHANIEL B. WALES, OF NEW YORK, N. Y., ASSIGNEES TO MICHIGAN SERVICE CORPORATION, OF JACKSON, MICHIGAN, A CORPORATION OF MICHIGAN.

CONSTRUCTION FOR PERFECTING COMBUSTION.

1,331,393.

Specification of Letters Patent.

Patented Feb. 17, 1920.

Application filed December 1, 1919. Serial No. 341,657.

To all whom it may concern:

Be it known that we, HARRY M. SNOW, residing at Kalamazoo, in the county of Kalamazoo and State of Michigan, and 5 NATHANIEL B. WALES, residing at New York city, in the county and State of New York, citizens of the United States, have invented certain new and useful Improvements in Construction for Perfecting Combustion, of 10 which the following is a specification.

This invention is based on the well known fact that in the burning of combustibles, such as coal and the like in furnaces no device or structure can so perfectly mix 15 comminuted fuel and air in combustible proportions when spread on a grate surface as to chemically proportion the mixture of air and carbon to give a complete oxidization to CO_2 of the air and carbon within the 20 immediate high temperature heat zone of the combustible mass due to reasons which will hereinafter be more clearly and in detail explained. This invention has for its 25 object structure which will bring about a separation of the CO gas from the CO_2 gas as the same are generated in varying proportions from a given condition of fire on the grates of a furnace due to the lighter specific gravity of the CO and by a proper 30 maintenance of temperatures of the gases, together with the addition of a controlled volume of highly heated air, which after separation of the CO from the CO_2 , is added in controlled volume to the CO gas, 35 resulting in the generation of very high temperatures at and beyond the point where the secondary burning takes place and which in operation resembles a torch-like sheet of flame starting with precision at the point 40 wherein conditions are arranged to produce it and giving its heat directly by impingement to the tube surface of the boiler.

On account of the inevitable clogging by ash and silica of grate openings and the natural packing of a solid fuel when subjected to 45 distillation, provision is made in this invention, as shown, in one embodiment of the same, providing for suitable openings in the vertical side walls of the fire box of the combustion chamber, just above the grate line, and below the top of the normal fuel bed, through which heated air is forced or induced either by the natural draft or by external means.

The coal is preferably fired on the grates, 55 which may be of any well known form and design, such that it lies in a relatively deeper mass near the side walls of the combustion chamber than at or near the center thereof and the advantage of this is clearly established in actual practice. The apertures in the side walls of the combustion chamber referred to not being easily clogged are effective in permitting a free passage of heated air to come in direct contact with the heavy 60 bank of coal lying against them. This coal naturally undergoes distillation of its more volatile components and forms mainly a CO gas, which being lighter than the CO_2 gas also generated in lesser degree, rises in the 65 fire box or combustion chamber to the top thereof. The result of this particular mode of firing with the coal banked against such side air openings produces a well defined 70 gas-producer action within the combustion chamber forming an excessive amount of CO gas, which gas now beyond the initial combustion zone is impelled upward due to its heated condition and light specific 75 gravity and is compelled to pass into a secondary 80 burner throat or nozzle wherein an additional volume of highly heated air mixes with it, said mixture being above its ignition point, immediately resulting in a torch-like flame sheet starting at the secondary burner 85 throat and extending through the heat path of the boiler.

It is evident that we may carry out this invention by proper arrangement of incorporated parts in any well known boiler and it is 90 one of the valuable features of this invention that this may be done, thereby permitting a great betterment of combustion in existing installations by making such changes in the brick work and setting of the boiler as to 95 effect this initial distillation and produce a secondary ignition zone, wherein the gases complete their combustion under conditions basically perfect for complete combustion.

One of the features which we wish to 100 plainly set forth in this invention is our preference to a relatively high combustion chamber and the setting of the boiler higher above the grate than is done in ordinary practice. This permits of a more effective 105 separation by weight of the carbon monoxide and other light gases from the carbon dioxide gas due to the greater distance or height be-

tween their respective exit passages. In many conditions of firing the boiler, there would occur periods of relatively low temperature distillation in which the monoxid 5 and other light gases would pass off from the top exit into the confining passage or nozzle below their temperature of ignition even after mixture with the heated fresh air and in order to insure the combustion of this 10 combustible mixture at such periods, the downward direction of the above mentioned nozzle or confining passage with its directions of flow of the monoxid gas directly counter to or through the flow of high temperature dioxid gas, which has passed directly from the combustion zone in the combustion chamber, insures at all times the proper ignition of the monoxid gas, this divergence of flow of the two streams producing 15 a commingling which insures the ignition of the monoxid gas.

For the purpose of illustrating one embodiment of our invention we shall refer to the accompanying drawings in which Figure 25 1 is a vertical sectional view of a water-tube boiler and a furnace constructed to carry out our invention; Fig. 2, is a front elevation of the furnace with the front wall broken away to show the construction of the baffle-arches, 30 the latter being also partly broken away to show the interior construction; and Fig. 3 is an enlarged detail view of the baffle arches.

The water-tube boiler and its setting are of a well-known type and consequently do 35 not require any description. The front wall 2 of the furnace setting is provided as usual with coal doors 4 and ash doors 5. The side walls of the fire box are preferably carried up higher than usual to provide a greater 40 depth of fire-box between the roof arch 6 and the grate bars 7.

The most efficient combustion is obtained when a large proportion of carbon-monoxid (CO) is produced in the fire-box which is 45 afterward combined with a supply of heated air to effect complete combustion. For this purpose of causing the production of a large amount of carbon monoxid we limit the intensity of combustion at the sides of the fire 50 box and supply the requisite amount of oxygen to combine with the volatile elements of the fuel by introducing air through openings 10 in the side walls, these openings connecting with air ducts 12 in the side walls 55 and having air inlets 14. The fuel is banked at the sides of the fire-box above the openings 10, the bed of coal being preferably thinner at the center of the grate. By firing 60 the grate in this manner the heat of combustion will be most intense along the center of the grate while at the sides the temperature of the fuel will be reduced by the streams of air entering through the openings 10, thereby 65 restricting the degree of combustion and resulting in a larger amount of distillation

of the fuel with the production of great quantities of carbon monoxid.

For the purpose of securing a separation of the heavier CO_2 gas from the lighter CO gas we provide a direct passage for the 70 heavier gases over the bridge-wall at the rear of the fire-box and an indirect channel for the lighter gases at the top of the fire-box. This is accomplished by constructing a forward baffle arch 15 which permits the 75 heavy CO_2 gas to pass thereunder directly into the flue passing through the tubes of the boiler, while the lighter CO gas naturally rises to the top of the fire box and passes over the top of the baffle arch. The space 80 above the opening under the arch therefore forms a zone of gravity separation between the monoxid and dioxid gases.

In order to effect a complete combustion of the monoxid and other light gases, we 85 construct a depending baffle wall 17 which extends downwardly from the top wall of the fire-box and which terminates in an arch slightly above the arch of the baffle-arch 15 thereby forming a narrow downwardly extending channel or throat 18 for the passage 90 of the CO gas. This narrow throat terminating just above the direct out-going flue passage under the rear baffle, causes the CO gas to sweep through the throat 18 with considerable velocity so that it intercepts the CO_2 gas with considerable force. The baffle-arch 15, and baffle wall 17 are tied together by connecting webs 22 inclosing tie-bolts and are provided with channels 20 and 21, 100 the latter connecting with a channel 23, extending through the roof arch of the fire-box. Each of these channels connects with the air supply channels 12 in the side walls. The air thus becomes highly heated and issues 105 in the form of hot blasts through the exit openings 20^a and 21^a upon opposite sides of the throat 18, mixing with the CO gas just before it meets the hot CO_2 gas coming from the grate. Under these conditions it is evident that the chemical union 110 of the CO gas with the oxygen of the highly heated streams of air issuing from the openings 20^a, 21^a results in an exceedingly violent torch-like blast of flame at the mouth 115 of the throat 18 which not only insures complete combustion of the CO gas but also consumes all volatile elements and unconsumed portions of the gases issuing with the CO_2 gas from the grate. While under normal 120 conditions the CO gas is at a sufficiently high temperature to combine with the hot air issuing from the openings 20^a, 21^a, yet in case it should not be, the highly heated CO₂ gas issuing from the grate serves to ignite 125 said CO gas as it emerges from the throat and intercepts said hot gas, thereby insuring the ignition of the mixture. It will be observed that the sheet or blast of burning gases issuing from the throat 18 and di-

rected rearwardly under the arch of the baffle 17 is located where it is most effective in heating the tubes of the boiler. We have therefore not only secured a perfect combustion of all of the gaseous and volatile products of the fuel but have also caused the most intense combustion to take place at a point where it will be most effective in heating the boiler.

10 It is desirable to provide an increased volume of air through the several air inlets when fresh fuel is being shoveled upon the grate and for this purpose the doors 4 may be connected by levers 25 and links 26, 27, 15 with dampers 28 in the air inlets, so that the dampers will be swung wide open when the doors are open and partially closed when the doors are closed.

We claim:

20 1. A boiler furnace comprising, in combination, a grate, a rear baffle depending from the furnace roof and terminating short of the grate, and a forward baffle spaced from said roof and rear baffle to form a passage and extending below the level of the edge of the rear baffle, said rear baffle containing an air inlet flue discharging into said passage, and the side walls of the furnace containing air inlet flues discharging into the fire-box over the grate and below the top of the normal fuel bed.

25 2. A boiler-furnace as set forth in claim 2, and damper mechanism for varying the inlets to said air flues.

3. A boiler-furnace as set forth in claim 2, damper mechanism for varying the inlets to said air flues and means connected with the furnace fuel door for controlling said damper mechanism.

4. A boiler-furnace as set forth in claim 2, damper mechanism for varying the inlets to said air flues and means connected with the furnace fuel door for controlling said damper mechanism.

5. A boiler furnace as set forth in claim 1, wherein the roof wall is provided with an air duct communicating with the air inlet flue in the rear baffle.

In testimony whereof we affix our signatures.

HARRY M. SNOW.
NATHANIEL B. WALES.
